[57] CLAIM

The ornamental design for a carrier plate for ribbed style cups, as shown and described.

DESCRIPTION

FIG. 1 is a top perspective view of one version of a carrier plate for ribbed style cups of my new design;

FIG. 2 is a left end view of FIG. 1, the other or right end being a mirror image thereof;

FIG. 3 is a top plan view of FIG. 1;

FIG. 4 is a front elevational view of FIG. 1;

FIG. 5 is a bottom plan view of FIG. 1;

FIG. 6 is a rear elevational view of FIG. 1;

FIG. 7 is a top perspective view of a second version of a carrier plate for ribbed style cups of my new design;

FIG. 8 is a left end view of FIG. 7, the other or right end being a mirror image thereof;

FIG. 9 is a top plan view of FIG. 7;

FIG. 10 is a front elevational view of FIG. 7;

FIG. 11 is a bottom plan view of FIG. 7; and,

FIG. 12 is a rear elevational view of FIG. 7.
